UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

LAMP LOCK-SOCKET.

1,277,533.

Specification of Letters Patent.

Patented Sept. 3, 1918.

Application filed October 7, 1914. Serial No. 865,467.

To all whom it may concern:

Be it known that I, REUBEN B. BENJAMIN, a citizen of the United States, residing at Chicago, in the county of Cook and State of Illinois, have invented new and useful Improvements in Lamp Lock-Sockets, of which the following is a full, clear, concise, and exact description, reference being had to the accompanying drawing, forming a part of this specification.

My invention relates to improvements in lamp lock sockets and has particular reference to means for locking the lamp in said socket against withdrawal.

For the purpose of disclosing my invention I have illustrated two embodiments thereof in the accompanying drawing. In said drawing—

Figure 1 is a plan view of an angle socket embodying my invention; the cap which covers the insulating base of said socket being removed to show the binding screws and the locking screw;

Fig. 2 is a section on the line 2—2 of Fig. 1, showing a lamp base locked in the socket;

Fig. 3 is a bottom plan view of the socket showing the semi-circular spring which carries the locking projection;

Fig. 4 is a side elevation of a special key used in locking and unlocking the lamp;

Fig. 5 is an end view of the key;

Fig. 6 is a plan view of a modification of my invention as embodied in a straight socket; and

Fig. 7 is a vertical axial section through the socket of the modification of Fig. 6, showing a lamp locked therein.

In Figs. 1, 2 and 3 I have illustrated my invention as embodied in an angle socket 10, that is, a socket whose axis is at an angle with respect to the conduit to which it is connected. Said socket comprises in general an insulating base 11 carrying binding screws 12 and 13 for the leading-in wires (not shown), a threaded shell contact 14 electrically connected by means of a screw 15 and binding plate 16 with the binding screw 12, a spring center contact 17 electrically connected with the binding screw 13, an insulating sleeve 18 surrounding the shell contact 14 and a casing 19 inclosing and housing the base and the parts carried thereby. The casing 19 includes a shell portion 20 having a tubular member 21 offset there-

from for connection with a conduit (not shown), through which the leading-in wires are brought to the channels 22 and 23 in the base 11 leading to the binding screws 12 and 13 respectively, and includes a removable cap 24 fitting over the shell 20 and held thereon in any suitable manner as by spring tongues 25 engaging within a bead 26 on the cap 24. The base 11 has an opening 27 therein and the shell contact 14 has an opening 28 therein, and through both of these openings extends an internally threaded sleeve 29, both ends of the sleeve being flanged over to hold the shell contact 14 and the base 11 together.

Interposed between the head of the screw 15 and a flange 30 on the shell contact 14 is a semi-circular leaf spring 31, said spring having an opening 32 through which the screw 15 extends and having at its free end a downwardly extending spur or prong 33 for engaging and biting into the lamp base 34. The spring 31 extends directly beneath the sleeve 29, and threaded in said sleeve is a screw 35, the point of which engages the spring 31 to force it downward. The tension of the spring is such as to tend to hold it up against the pressure of the screw 35. The screw 35 has a triangular head 36 for engagement with a correspondingly shaped socket 37 in the key 38 which is inserted in the recess 39 in the base 11 and fitted over the head 36 to turn the screw 35 in one direction or the other.

The use and operation of this modification is as follows: If it is desired to secure the lamp in the socket the cap 24 is removed from the shell 20, the key 38 is fitted to the screw 35 and the latter is backed away to allow the spring 31 to rest against the end of the sleeve 27. The lamp base is then screwed into the socket until its center contact is in suitable engagement with the spring contact 17. The screw 35 is then turned to bear down on the top of the spring 31 to force the prong 33 to engage and bite into the lamp base. The key is then withdrawn and the cap 24 snapped in place. The engagement between the prong 33 and the lamp base renders it practically impossible for an unauthorized person to unscrew the lamp to remove it from the socket.

It is to be noted that there is nothing about the external appearance of the socket

to indicate that it is provided with a lamp locking device; that the sleeve 27 and screw 30 which hold the shell contact 14 on the lock-base 11 are also utilized to support the locking spring 31 and the lock actuating screw 35, and that even if an unauthorized person knew that it was necessary to loosen the screw 35 before removing the lamp that this could not be done without a special key 10 which would enter the recess 39 and fit the head 36.

In the modification of Figs. 6 and 7 I have illustrated my invention as embodied in a straight socket, that is, a socket having its axis in line with the axis of the conduit 15 for the leading-in wires, and have omitted the pronged spring between the screw and lamp base.

In this modification the socket comprises an insulating base 40 having secured thereto by means of a hollow rivet 41 and screw 42 the usual shell contact 43 and also having secured thereto the usual center contact 44, and comprises also a casing 45 including a shell 46 and a cap 47 fitting over said shell and detachably secured thereto in any suitable manner. The cap 47 has a tubular member 48 extending axially therefrom for securing it to a conduit for the leading-in 20 wires (not shown). Threaded in the hollow rivet 41 is a screw 49 having a triangular head 50 for engagement with the key 38; the point of the screw 49 bears directly on the lamp base 50^a. The cap 47 has an opening 51 therein in line with the screw 49 through which the key 38 may be inserted. Rotatably mounted on the cap 47 is a closure member 52 held in place between the tubular portion 48 and the body of the cap 40 47. The closure member 52 has an opening 53 therein which may be brought into registration with the opening 51 so that the key 38 may be inserted through said opening to operate the screw 49.

45 In this modification I have inclined the screw 49 somewhat to bring the head 50 into proper position and to secure a good bearing of the point of the screw on the lamp base 50^a.

50 The use of this modification of my invention is as follows: If it is desired to secure a lamp in the socket the cap 47 is rotated to bring the opening 53 into registration with the opening 51, the key 38 is inserted and the screw 49 is backed away to a position which will permit the proper insertion of the lamp. The lamp base 50^a is screwed into the socket and the screw 50 operated to cause the point thereof to engage and bite into the lamp base. The key 55 is then withdrawn and the closure member 52 rotated to move the opening 53 out of registration with the opening 51.

55 In both modifications it is to be noted that the head of the locking screw is normally

concealed and that it must be operated from the end of the socket opposite that in which the lamp base is inserted.

It is to be noted too that in the modification of Figs. 1, 2 and 3 the prong 33 as shown in Figs. 2 and 3 is so inclined as to offer little resistance to the movement of the lamp base when the latter is being screwed into the socket, but so as to offer much greater resistance when it is attempted to unscrew the lamp from the socket so that even if the screw 35 is in such a position that the spring 31 is held away from the sleeve 29 the lamp base may still be screwed into the socket a sufficient distance to make 80 proper contact with the spring contact 17.

Having thus described my invention what I claim as new and desire to secure by Letters Patent is:—

1. A lamp socket including an insulating 85 base, means for locking a lamp base in said socket including a screw carried by said insulating base, and closure means for preventing access to said screw.

2. A lamp socket including an insulating 90 base having a shell contact secured to one face thereof, and means for securing a lamp base in said socket including a screw having its head exposed on the opposite face of 95 said insulating base.

3. A lamp socket including an insulating base having a shell contact secured to one face thereof, means for securing a lamp base in said socket including a screw having its head exposed on the opposite face of 100 said insulating base, and closure means for preventing access to said screw.

4. A lamp socket including an insulating base, a shell contact, means for securing said shell to said base including a hollow rivet, 105 and means for locking the lamp in said shell including a screw threaded in said hollow rivet.

5. A lamp socket including an insulating base, and means for locking a lamp in said 110 socket including a leaf spring secured at one end to said base, and a screw having its point bearing on the free part of said leaf spring for forcing it into engagement with the lamp base.

6. A lamp socket including an insulating base, a shell contact, means for locking a lamp in said shell including a spring, and means common to said shell and spring for securing them to said base.

7. A lamp socket including an insulating base, a shell contact, means for locking a lamp in said shell including a spring, and means common to said shell and spring for securing them to said base including a 125 screw.

8. A lamp socket including an insulating base, a shell contact, means for locking a lamp in said shell including a spring, means common to said shell and spring for securing them to said base including a 130 screw.

ing them to said base including a screw, and a binding screw electrically connected with said first screw.

9. A lamp socket including an insulating base, a shell contact, a center contact secured to said base, means for securing said shell to said base including a hollow rivet, and a screw on opposite sides of said center contact, a curved spring having one end secured to said screw and extending around said

center contact, and a screw threaded in the said hollow rivet and engaging the other end of said curved spring.

In witness whereof, I have hereunto subscribed my name in the presence of two ~~15~~ witnesses.
